UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

FLUID-PRESSURE TANK.

Application filed February 26, 1921. Serial No. 448,239.

My invention relates to fluid-pressure tanks and particularly to means for ventilating such tanks and for maintaining the pressure therein within predetermined limits.

5 The object of my invention is to provide an arrangement of automatic valves whereby a tank is opened to the atmosphere under predetermined conditions and whereby such tank is automatically sealed against communication 10 with the atmosphere under certain other predetermined conditions.

More particularly stated, my invention contemplates the maintenance of communication 15 between a tank and the atmosphere during the time that the pressure within the tank does not exceed atmospheric pressure and for automatically effecting a closure of the tank against communication with the atmosphere during the time that the pressure within the 20 tank is within predetermined limits. When pressure within the tank rises above a predetermined point, communication will again be established between the atmosphere and the interior of the tank, to permit the venting 25 of excess pressure.

In the preferred form of my invention, I employ a plurality of vents so arranged that the circulation of air through the tank to clear the same of gases is facilitated during 30 the time that there is no pressure in the tank.

The single figure of the accompanying drawing is a view, partially in elevation and partially in section, of a tank with my improved form of vent control applied thereto.

35 For purposes of illustration, I have shown my apparatus as applied to a tank 1, such as may be used in connection with an electric circuit breaker, to contain oil or other fluid for quenching the arcs which may be formed 40 during the opening or the closing of the breaker (not shown).

A casing 2 is provided for housing the operating mechanism for the contact members that are supported within the tank 1, communication being effected between such casing and tank by means of a tubular connection 3. Both the tank 1 and the casing 2 are sealed against communication with the atmosphere, except for the vents which will 50 hereinafter be described.

The tank 1 is provided with a vent, as shown, such vent being surrounded by a casing 4 that is bolted to the top of the tank 1. A pair of valve members 5 and 6 are pro-

vided within the casing 4. The valve member 5 is normally held against its seat by a compression spring 7 that is, in turn, held securely in place by a pair of bolts 8 and a cross-head 9.

The interior of the tank 1 is normally in 60 communication with the atmosphere, through an opening 10 and a stack 11 which is provided to convey the fumes from the interior of the tank to a convenient distance.

The valve 6 is slidably supported in a 65 bracket 12 that is secured to the valve member 5, and it acts as a check valve. A vent-controlling apparatus 13 is provided for the casing 2 and is identical in construction and operation with the apparatus just described 70 for controlling the vent of the tank 1.

The valves of both the tank 1 and the casing 2 normally occupy the positions illustrated, and air may freely circulate through the tanks and the casing. The mounting of 75 the one vent in a higher plane than the other serves to facilitate the circulation of air to cleanse the interior of the tank 1 and the casing 2 of gases.

When the body of liquid within the tank 1 80 is heated, by reason of the formation of an arc between the contact members, pressure is created within the tank and is directed against the check valves 6 and the disc-like members 14 that are carried thereby, thus 85 causing the valves 6 to seat against the under side of the valve members 5, cutting off communication between the interior of the tank and the atmosphere. As the pressure within the tank increases, the arc is extinguished 90 but, if such pressure increases to a point above which it may not safely go without danger of rupturing the tank, the valve members 5 are carried upward against the compression of the springs 7, thus permitting the excess 95 pressure to escape. As soon as the pressure within the tank dies down, the valves return to the positions illustrated in the drawing, and the tank and the casing are once more open to the atmosphere to permit circulation 100 of air therethrough.

The pipe 11, besides serving to conduct the gases of combustion away from the vicinity of the tank, may also serve as an oil saver in case an explosion takes place within the 105 tank and oil is thrown through the vents.

Various modifications may be made in the design of the apparatus without departing

from the spirit of the invention. For instance, only one spring-held valve member need be provided, and but one check valve is necessary save in so far as a plurality of openings are desirable in order to secure an effective circulation of air through the tank. Furthermore, the vents may both be mounted on the tank itself and need not necessarily occupy different horizontal planes. Other 10 modifications will be apparent to those skilled in the art.

I claim as my invention:—

1. An electrical device provided with a vent to permit the escape of gases therefrom, 15 said vent being provided with closure means for confining the gases within the device during the time that the pressure of such gases remains within predetermined maximum and minimum limits.
2. A fluid-filled electrical device provided with a two part venting device one part of 20 which is provided with closure means for confining the fluid in the device during the time that the pressure of such fluid exceeds a predetermined limit, and the other part of which 25 is provided with closure means adapted to re-

lease the fluid from the device when the pressure of such fluid exceeds a predetermined further limit.

3. An electrical device provided with a two 30 part venting device one part of which is provided with a valve adapted to close under a predetermined pressure from within the device and the other part of which is provided with a valve adapted to open when the pressure within the device reaches a predetermined value.

4. The combination with a vent for a fluid-pressure tank, of a valve therefor provided with enlarged portions, respectively disposed 40 interiorly and exteriorly of the tank, one of said enlarged portions being adapted to seat against the wall of the tank to close said vent, and the other enlarged portion being adapted to be acted upon by the passage of 45 fluid pressure through said vent whereby said valve is moved to its closed position.

In testimony whereof, I have hereunto subscribed my name this 15th day of February, 1921.

CHRISTIAN AALBORG.
